RECORDING APPARATUS

Julius Allardt, Altona-Blankenese, Germany

Application January 10, 1938, Serial No. 184,322
In Germany April 6, 1936

3 Claims. (Cl. 88—24)

This invention relates to an apparatus for the convenient transfer of booked entries from a general list of such entries on to classified accounts or registers, and the invention consists in effecting the transfer by optical means for instance photography, for which purpose the list is fed intermittently through a guideway having an exposure window with which photographic cameras provided with film strips, are selectively aligned, this being effected by co-operating controlling means on the list and on the guideway. Means are also provided for transferring an entry on to more than one account or register.

The construction of the apparatus and the means whereby it is operated may be subjected to considerable modifications. In the accompanying drawings the invention is illustrated in connection with an electrically controlled apparatus having means for transferring entries from a continuous list fed from a delivery on to a take-up roller and provided with apertures whereby the mechanism is controlled.

Fig. 1 of said drawings represents a side view of the apparatus,

25 Fig. 2 is a front view thereof,
Fig. 3 is a section on the line 3—3 of Fig. 1,
Fig. 4 is a section on the line 4—4 of Fig. 2,
Fig. 5 is a section on the line 5—5 of Fig. 1,
Fig. 6 shows part of Fig. 3 on an enlarged scale,
30 Fig. 7 is a detail view on an enlarged scale,
Fig. 8 is an enlarged view, partly in section, of the list feeding mechanism,
Fig. 9 is a detail view,
Fig. 10 is a side view of the camera mechanism,

35 Fig. 11 is a detail view of this mechanism seen at right angles to Fig. 10.
Fig. 12 is a plan view of the camera mechanism, partly in section on the line 12—12 of
40 Fig. 10, and

Fig. 13 is a diagrammatic view showing the electric connections.

In the illustrated arrangement the apparatus comprises a delivery spool 13 and a take-up spool 45 18 for the paper strip 14 bearing a list of printed or written entries which are to be classified. On its way from one spool to the other, the strip passes through a guideway in which there is a window 20 illuminated by a lamp 21. In this window the entries on the list 14 are exposed for the photographic transfer of the entries to their respective accounts or registers. For this purpose a plurality of photographic cameras 8 are in the present instance mounted radially in even distribution on a holder in the form of a

disc 32 which is mounted rotatably on a shaft 82 and constructed as a worm wheel, it being in operative engagement with a worm 31 driven by an electric motor M. The holder 32 is arranged so as to move the cameras in succession through a position of alignment with the window 20 for photographing the entries appearing in the latter.

The feeding of the list 14 is effected by means of feed roller pairs 15, 16 and 17 some of which have sprockets for engagement in known manner in edge apertures made in the paper strip. The rollers are geared together, and the principal roller 15 is fitted with a spur gear 67 (Fig. 8) which meshes with a gear 66 connected to a ratchet wheel 61. A hand lever 56, which is operated once for each entry, reciprocates, in co-operation with a spring 7, a rod 57 fitted with a pawl 60 which engages the ratchet wheel 61 for rotating the gears and the feed rollers. Each 20 such operation of the lever 56 causes the list 14 to be advanced so as to bring a fresh entry into view in the window 20.

On its way to the feed rollers, the list 14 passes across a tracker bar 19 which is suitably connected to a source of suction and which is provided with a row of apertures. For each entry on the list to be transferred, there is on the list an aperture which registers with one of the apertures on the tracker bar when the respective 30 entry is exposed in the window 20. A block 9 between which and the tracker bar the list 14 passes, is provided with channels which register with the apertures in the tracker bar. These channels are controlled by a rotary three-way 35 valve 6, and a pinion 59 connected to the valve meshes with a gear wheel or sector 53 which is connected to the bar 57 so as to be rocked by the latter. On the lever 56 being moved into the position shown in Fig. 8, the ratchet wheel 40 61 is turned for advancing the list 14, and at the same time the valve 6 is turned so as to form straight channels through the block 9. When the hand lever returns to its initial position, the outer ends of the channels are connected through passages 10 with the atmosphere. At the outer end of the blocks the channels terminate in pipe connections 12 which communicate through pipes 11 and through pipe connections 76 with cylinders 22 secured in uniform 50 distribution to the circumference of a circular frame 27 which is coaxial with and arranged near the rotary camera holder 32. The latter is fitted with two electric contact rings 28 and 29 which are swept by an arm 30 connected to the 55

holder 32. Referring to the diagram in Fig. 13 it will be seen that the rings 28 and 29 are connected to the positive pole of an electric source and that the motor M is fed with current through a circuit traced through the leads a and b, the rings 28, 29, the arm 30, a lead c, a sliding contact 74, and leads d and e. Thus the motor and holder 32 will be maintained in motion when the circuit is closed by a switch 75.

Under each cylinder 22 (Fig. 6) there is a gap in the ring 28 which gap is normally filled in with a segment 25 carried by a double-armed lever 33. The latter is connected by a spring-controlled rod 17 to a piston 23 located in the cylinder 22. When an aperture in the list 14 is in register with one of the channels in the block 9, suction will be applied to the respective cylinder 22, and the piston 23 will then be raised so as to lift the segment 25 from its position in the ring 28 and break the continuity of the latter. Opposite the gap in the ring 28 there is a patch of insulation on the ring 28 so that, when the arm 30 arrives at the gap, the motor circuit will be broken and the camera holder 32 will come to a standstill. When this happens, one of the cameras 8 will be in alignment with the window 20 for photographing the entry appearing in the latter.

Each camera contains a film strip 82 (Fig. 10) whereon the entries are photographed. The strip is fed from a spool 78 on to a spool 79 by means of a feed roller 46 which, together with a guide roller 80, holds a portion of the strip in the focal plane of the camera lens 54. The roller 46 is connected to a ratchet wheel 45 which is engaged by a pawl 44 connected to an operating lever 43. The latter carries the armature of an electro-magnet 42 which actuates the lever and which is energized in the following manner:

An electro-magnet 36 is mounted in a stationary position within the circular path traced by the cameras and arranged so as to be in alignment with any camera that stops in front of the exposure window 20. The armature of the magnet is connected to a spring-controlled rod 37 carrying two electric contacts 38 and 39 which are connected to the electric source and which, when the armature is attracted by the magnet, are moved into engagement with corresponding contacts 40 and 41 carried by the camera in front of them. The contact arm 30 of the camera holder 32 is fitted with a contact 35 (Fig. 6) which is connected by a lead f (Fig. 13) to a sliding contact 81 which in its turn is connected through the magnet 36 with the positive pole of the electric source. The lever 33 carries a contact 34 which is connected to the negative pole of the source and which, when the lever is operated for breaking the continuity of the contact ring 28, is moved into position to be engaged by the contact 35. Thus, as the circuit of the motor M is broken, the circuit of the magnet 36 will be closed through the leads a and g, magnet 36, lead h, contact 81, lead f, contacts 35 and 34, and leads i and e. The rod 37 is then thrust forwards by the armature of the magnet 36, and as the contacts 38 and 39 engage the contacts 40 and 41, the following circuit will be closed: Leads a and k, contacts 38 and 41, magnet 42, contacts 40 and 38, and lead l. The armature of the magnet 42 will then be attracted, and the ratchet wheel 45 will be operated for feeding the film strip one step forward. As the lever 43 is rocked for this purpose it connects by means of a contact 47 two leads o and p and thus closes a further circuit

through the contact 41, a lead n, a magnet 48, the lead p, the contact 47, the lead o and the contact 48, and the magnet 48, on attracting its armature, operates a spring-controlled lever 49 and a pawl 50 so as to turn a ratchet wheel 51. The latter acts by means of a conical gear 52 on a rotary shutter 53 by which the lens aperture is momentarily cleared for making the photographic exposure. On the hand lever 56 being restored to its initial position, the valve 6 sets the cylinder 22 in communication with the atmosphere, whereupon all the other elements are also restored by their springs to normal position, ready for the next exposure. A pilot lamp 55 arranged in the lead l lights up to indicate that the photographic mechanism is in operation.

It may be desired to transfer an entry on to more than one register, and for this purpose the following arrangement is provided:

Referring to Fig. 5 it will be seen that the feed roller 15 transmits motion to the rollers 16 and 17 through the medium of a shaft 64 and a set of conical gears. The driving gears 83 and 84 for the rollers 16 and 17 are mounted on a sleeve 65 which is loosely arranged on the shaft 64 and coupled to the latter through the medium of a spring barrel 69. The latter has a toothed rim 70, and a spring-controlled plunger 68 is adapted to be urged by a magnet 71 into engagement with the rim so as to prevent the spring barrel and thus the feed rollers 16 and 17 from moving. When this happens, and when the hand lever 56 is operated for feeding the list across the tracker bar 19, the resulting operation of the camera mechanism will be to move two or more cameras 35 successively into position to receive the image of the entry retained in the window 20. In the meantime the list 14 will be slackened between the feed rollers 15 and 16, but as soon as the spring barrel 69 is released, it will even out the slack. For the automatic operation of the plunger 68, the following arrangement is provided:

A spring-controlled feeler 72 (Fig. 9) is pivoted to the block 9 and arranged to bear against the list 14 opposite a contact member 2 (Fig. 13) let into the tracker bar 19. For each entry on the list to be thus transferred to several registers, the list is provided with an aperture allowing the feeler 72 to touch the contact 2, and a circuit 50 will then be closed through the lead a, the magnet 71, a lead q, the contact 2, feeler 72, a lead r, and the lead e. The magnet 71 then operates so as to retain the particular entry in the exposure window for repeated exposures. If more than two exposures are to be made from the same entry, the respective apertures in the list may be combined into a single, elongated aperture. As soon as the list again intervenes between the contact member 2 and the feeler 72, the spring barrel 69 will be released.

The photographic negatives obtained in this manner are subsequently printed and may be suitably enlarged.

The apparatus may be subjected to modifications within the scope of the invention as defined by the appended claims. For instance the entries to be transferred may be made on cards passed in succession through the guideway. The controlling apertures in the list may be replaced by metallic contacts for closing the different circuits, and means may be provided for moving the guideway relative to the group of cameras instead of vice versa.

I claim:

1. An apparatus for the photographic transfer of booked entries from a general list of such entries on to classified registers, comprising a guideway for the list having an exposure window, means for illuminating said window, means for feeding the list intermittently past said window, a photographic camera for each register, a rotary holder for the cameras arranged to move the latter successively into alignment with the exposure window, means for rotating said holder, selectively co-operating controlling means on guideway and list for interrupting the rotation of the holder with a camera in alignment with the exposure window, a film strip in each camera, electrically controlled means for operating an aligned camera to photograph a list entry in the window, and electrically controlled means for advancing the strip after each exposure.
2. The structure claimed in claim 1 in com-

bination with means, controlled by the list, for causing selected entries to be photographed successively in more than one camera.

3. A structure as claimed in claim 1 wherein the controlling means on the guideway are arranged at a distance from the exposure window and wherein the list feeding means are divided between the window and the controlling means into two sections, a spring coupling communicating motion from one section to the other, electrically operated means for arresting one section so as to maintain a list entry stationary in the window while another portion of the list moves for bringing a plurality of cameras successively into operative alignment with the window, and switching means controlled by the list for throwing said arresting means into and out of operation.

JULIUS ALLARDT. 20
